US00D910937S

(12) **United States Design Patent** (10) **Patent No.:** **US D910,937 S**
(45) **Date of Patent:** **** Feb. 16, 2021**

(54) **PET NAIL GRINDER**

(71) Applicant: **SHENZHEN JOYU APPLIANCE CO., LTD.**, Shenzhen (CN)
(72) Inventor: **Zhuhui Wei**, Shaowu (CN)
(**) Term: **15 Years**
(21) Appl. No.: **29/714,547**
(22) Filed: **Nov. 25, 2019**
(51) LOC (13) Cl. **30-99**
(52) U.S. Cl. **USPC D30/158**

(57) **CLAIM**

The ornamental design for a pet nail grinder, as shown and described.

DESCRIPTION

FIG. 1 is a front perspective view of a pet nail grinder, showing my new design;

FIG. 2 is a front and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front perspective view of the pet nail grinder with a lid detached.

The broken lines in the figures illustrate portions of the pet nail grinder that form no part of the claimed design. The broken lines in FIG. 9 depict an exemplary lid component for illustrative purposes and form no part of the design claim.

1 Claim, 9 Drawing Sheets
